UNITED STATES PATENT OFFICE.

GEORGE H. BABCOCK, OF PLAINFIELD, NEW JERSEY.

DESIGN FOR A ROOFING-TILE.

SPECIFICATION forming part of Design No. 20,407, dated December 16, 1890.

Application filed October 28, 1890. Serial No. 369,620. Term of patent 14 years.

To all whom it may concern:

Be it known that I, GEORGE H. BABCOCK, a citizen of the United States, residing in Plainfield, in the county of Union and State of New Jersey, have invented and produced a new and original Design for Roofing or Sheathing Tiles, of which the following is a specification, reference being had to the accompanying drawings, forming a part thereof.

10 The design relates to a clay or other tile in which the ornamental effects are produced by its contour.

15 The design consists of a tile the outline of which is substantially of Gothic form and its surface of a shallow dished contour, rising gradually toward the lower edges of the tile.

20 In the accompanying illustrations, Figure 1 illustrates a face view of a tile of the new design; Fig. 2, a transverse vertical section of the same; Fig. 3, a cross-section taken on the line 3-3 of Fig. 1, and Fig. 4 a similar section on the line 4.

25 The design relates particularly to the exposed or lower face of a tile, its upper portion partaking of various shapes.

As illustrated, the tile is substantially of Gothic outline, having its two upper edges inclined and bearing upper flanges *a b*. The two lower edges *c d* are curved and terminate in a point. Near the upper edges of the tile 30 the surface is substantially straight to the curved lines *e f*, at which point the surface is suddenly dished toward substantially the center of the tile, when the surface gradually rises in easy curves until it meets the inclined edge *g*. This inclined edge has its greatest height at or near the lower end of the tile, and merges at its upper ends into the substantially flat portion of the tile bounded by the lines *e f*. 35

40 What is claimed is—

The design for a tile, substantially as described and shown.

45 In witness whereof I have hereunto set my hand, this 2d day of October, A. D. 1890, in presence of two witnesses.

GEO. H. BABCOCK.
